UNITED STATES PATENT OFFICE.

ELTON F. KILBOURN, OF ALLERTON, IOWA.

FARROWING PEN.

Application filed May 25, 1923. Serial No. 641,464.

To all whom it may concern:

Be it known that I, ELTON F. KILBOURN, a citizen of the United States, residing at Allerton, in the county of Wayne and State 5 of Iowa, have invented new and useful Improvements in Farrowing Pens, of which the following is a specification.

This invention relates to improvements in farrowing pens, the general object of the 10 invention being to provide a device which is adapted to be placed in the pen and which is so constructed that the small pigs can go into the same so that they are protected from being injured by the sow and at the same 15 time are kept warm.

Another object of the invention is to provide the device with heating means and a detachable curtain for retaining the heat therein.

20 This invention also consists in certain other features of construction and in the combination and arrangement of the several parts, to be hereinafter fully described, illustrated in the accompanying drawings and 25 specifically pointed out in the appended claim.

In describing my invention in detail, reference will be had to the accompanying drawings wherein like characters denote like 30 or corresponding parts throughout the several views, and in which:—

Figure 1 is a plan view of a farrowing pen showing the invention in use.

Figure 2 is a section on line 2—2 of Figure 35 1.

Figure 3 is an enlarged side view of the device itself, the curtain being partly raised.

Figure 4 is an enlarged plan view with parts broken away.

40 Figure 5 is a sectional detail view.

Figures 6, 7 and 8 are views of a modified form of the device.

Figure 9 is a sectional detail view showing another means for fastening on the curtains.

45 In these views A indicates the pen and B the device which forms the subject matter of the invention. This device is formed of a framework 1 which consists of the bottom part 2, the top part 3 and the upright pieces 4 which connect the bottom and top parts together. Each of the bottom and top parts are composed of the triangular shaped portions 5 and the straight piece 6 which is connected with the apex of the triangle.

Braces 7 may also be used wherever necessary. A cover 8, preferably of oval-shape is fastened to the top part of the frame and this cover is of greater dimensions than the frame so that it will project well beyond the frame. A curtain 9 is detachably connected with the edges of the cover, preferably by hooks and eyes 10 so that it may be detached when necessary. Projections 11 are also placed on the edges of the cover to prevent the sow from lying against the device. A length of barbed wire may be fastened to the cover in lieu of these projections. A chamber 12 is formed in the top of the frame under the cover for receiving a 70 hot brick or a piece of soap stone, so that the interior of the device can be heated. The curtain will hold this heat in the device.

The device is placed in the pen in such a position that the sow can make her bed 75 alongside of the device. Thus the pigs can remain under the device and thus the danger of the sow crushing the pigs is removed. The sharp projections on the device will prevent the sow from lying down with her 80 back to the device so that the pigs can readily feed. When the weather is not cold the curtain can be removed.

In the modification the frame 1' is made of triangular shape and the cover 8' is of 85 substantially circular shape but in other respects this form of the invention is similar to that before described.

In both forms the device is firmly held in the pen by a pole 13 which passes through 90 the hole 14 in the cover and has its ends secured to the floor of the pen and a cross piece or rafter at the top of the pen.

Figure 9 shows the curtain as being held in place by a wire clamping ring 15 which 95 passes through a loop 16 formed in the curtain.

The device is placed in the center of the pen so that the sow may pass around it and the device will prevent the sow from walking over the pigs or lying down upon them. The curtain is not put in place until after the sow has made a bed as otherwise she might pull the curtain off to use it as part 100 of her bed.

105 It is thought from the foregoing description that the advantages and novel features of my invention will be readily apparent.

I desire it to be understood that I may 110 make changes in the construction and in the

combination and arrangement of the several parts, provided that such changes fall within the scope of the appended claim.

What I claim is:—

- 5 In combination with a farrowing pen, an open framework placed therein and consisting of upper and lower members and upright pieces connecting the members to-

gether, a cover plate supported on the upper member and projecting beyond the same so that the pigs can pass under the same and through the framework and a depending curtain connected with the edge of the cover.

10 In testimony whereof I affix my signature.

ELTON F. KILBOURN.
